(57) **CLAIM**

The ornamental design for a lift off hinge, as shown and described.

DESCRIPTION

FIG. 1 is a perspective view of my new design for a lift off hinge;

FIG. 2 is an exploded view thereof embraced by a bracket, forming no part of the claimed design, but indicating the relationship and order of the separated parts;

FIG. 3 is a top view of FIG. 1;

FIG. 4 is a front view of FIG. 1, a back view being the same; and,

FIG. 5 is a right side view of FIG. 1, a left side view being the same.

The bottom surfaces of the lift off hinge form no part of the claimed design.
